UNITED STATES PATENT OFFICE.

WALTER J. F. LIDDELL, OF CHARLOTTE, NORTH CAROLINA.

SAW-MILL DOG.

SPECIFICATION forming part of Letters Patent No. 285,824, dated October 2, 1883.

Application filed June 16, 1883. (No model.)

To all whom it may concern:

Be it known that I, W. J. F. LIDDELL, of Charlotte, county of Mecklenburg, State of North Carolina, have invented a new and useful Improvement in Saw-Mill Dogs, of which the following is a full, clear, and exact description, reference being had to the accompanying drawings, making part of this specification.

10 My invention relates to that class of mechanism which is designed to hold materials upon the carriage of a saw-mill in proper position to be operated upon by the saw; and the object of the invention is to produce a simple 15 and efficient mechanism for the purpose stated which shall be capable of very considerable adjustment, in order to receive materials of different widths, and the several functions of which shall be performed in consequence of 20 manipulations of a single operative member.

To the above ends my invention consists in the provision of a mechanism in which two dogs are arranged, one above the other, within a suitable standard, the lower dog being attached to the lower portion of a vertical rack-bar placed within the said standard in such manner as to have a limited vertical movement, and the upper dog being attached to a carrier-block, also confined within the said standard, 25 and moving freely in a vertical plane upon the rack-bar, and an operating-lever pivoted upon said carrier-block and engaging directly or indirectly with the said rack-bar, for the purpose of holding the carrier-block at any desired point of its movement, while permitting 30 the unimpeded movement of said block when so desired.

My invention further consists in the provision of certain devices for retaining the carrier-block at the upper limit of its permitted 40 vertical movement, and for holding the operating-lever out of engagement with the rack-bar during the retention of the carrier-block.

My invention further consists in so arranging 45 the upper dog that, when idle, it may be retracted so as to bring its outer end flush with the front face of the standard, for the purpose of avoiding obstruction to the board while being placed in position.

50 My invention further consists in certain details of construction, hereinafter described and claimed.

In order that my invention may be fully understood, I will proceed to describe it with reference to the accompanying drawings, in 55 which—

Figure 1 is a side elevation of my improved mechanism, the near section of the standard being removed to expose the interior devices. Fig. 2 is a vertical longitudinal section through 60 the base and carrier blocks, the parts being in operative position upon the rack-bar. Fig. 3 is a top view of the carrier-block and operating-lever in detached position. Fig. 4 is a side elevation of one of the sections of the 65 standard, showing the vertical guides upon the inner side. Fig. 5 is a side elevation of one of the standard-sections, showing the manner of attaching the lever-stop. Fig. 6 is a top view of the standard, the working parts 70 being removed, showing the suspending-bar. Fig. 7 is a side elevation of a modified form of mechanism, the near section of the standard being removed and the parts being in operative position. Fig. 8 is a vertical section of 75 the same. Fig. 9 is a side elevation of a modified form of standard for the mechanism shown in Fig. 8. Fig. 10 is a rear elevation of the modified carrier. Fig. 11 is a horizontal longitudinal section of the modified operating- 80 lever. Fig. 12 is a side elevation of the modified carrier and operating-lever, showing the opposite side from that shown in Fig. 7.

In the said drawings, A designates the carriage of my improved mechanism, arranged to 85 slide longitudinally upon suitable guide-rails, A', and carrying upon its forward end the standard B. This standard is composed of two vertical parallel sections having each a vertical shoulder, b, at the front edge of its outer 90 side. On its inner side each of these sections is formed with two parallel vertical guides, b' b'', the former of which extends the entire length of the section, while the latter tapers off and terminates some distance lower down. 95

C designates a rack-bar, one side of which is formed with a continued series of teeth, c, extending from its top downward nearly to its base. At the lower end of this rack-bar is formed a square enlargement or block, C', which carries 100 the lower dog, D, to be presently described. The rack-bar C stands vertically between the two sections of the standard B, and is held in position partly by a bolt or pin, 1, which passes

transversely through the sides of the standard, and also through a vertical slot, c' , formed horizontally through the block. It will thus be seen that the bar C will be capable of a slight vertical movement upon the pin 1 equal to the difference between the length of the slot c' and the diameter of the pin 1. Furthermore, the distance between the two guides $b'b^2$ is sufficiently greater than the width or depth of the block to permit a slight transverse movement of the latter. The purposes of these arrangements for permitting movements of the block C' will be hereinafter stated. The lower dog, D, is seated in a vertical groove, c^2 , which extends throughout the length of the block, its bottom being flush with the edge of the rack-bar, and its sides tapering off at their lower ends, as shown. A tail-pin, d, is inserted through the body of the block C', and enters the body of the dog in such manner as to be removable, so as to permit the dog to be detached from the block.

C^2 designates the carrier-block for the upper dog, D', and also for the operating-lever E, hereinafter described. This block is formed with rabbets c^3 , extending vertically upon its four corners, as shown, the shoulders of which play loosely between the vertical guides $b'b^2$, for a purpose hereinafter described. At its upper end this block is formed with a projecting ledge, c^4 , which overhangs the rear side of the block, and upon this ledge is formed a triangular stud, c^5 , placed apex out, as shown, the upper side of the ledge c^4 being beveled off to correspond with the slope of the upper side of the stud c^5 . At the rear face of the block C^2 is formed a recess, c^6 , to receive the inner end of the operating-lever E, presently to be described. Through the upper and lower ends of the block C^2 are formed apertures c^7 , opening above and below into the recess c^6 and designed to receive the rack-bar C. An opening, c^8 , is formed horizontally through the upper part of the block C^2 , from front to back thereof, and constitutes the socket for the dog D'. This dog is formed with a shank having an opening, d' , formed centrally through it in a vertical direction, and corresponding in form and position with the upper aperture, c^7 , through which the rack-bar passes. At the rear end of the shank are two projections, d^2 , in the form of down-turned hooks, each of which is provided at its lower portion with an eye, through which passes a key, 2, resting against the rear side of the block C^2 when the dog is attached to said block, the arrangement being such as to permit of the detachment of the dog from the block when so desired.

3 designates a pin which passes transversely through the standard, suitable holes being formed in the sides of the standard to receive said pin. One end of this pin is formed with a screw-head, while the opposite end is formed with a screw-thread, the corresponding hole of the standard being threaded internally to receive the thread of the pin. When the pin 3 is screwed into position, as shown, it consti-

tutes a brace for the upper ends of the sections of the standard, also the means for retaining the block C^2 at the upper limit of its movement, as hereinafter described, and also the means for attaching the stop-piece C^3 . This stop-piece is made of such length that, when the projecting threaded end of the pin 3 is inserted into its eye, its rear end shall rest against the shoulder b of the standard, and thus be prevented from tilting upon the pin. The piece C^3 is further secured against displacement by a nut, 3 ^{2} , screwed upon the threaded end of the pin 3, between which and the side of the standard the stop-piece is confined. The opposite end of the piece C^3 is turned at right angles, so as to extend across the face of the standard and act in connection with a spur upon the operating-lever, as hereinafter described.

E designates the operating-lever, which may be of an approximately S shape, as shown. At its inner end this lever is formed with a series of gear-teeth, e, and also with an eye which receives a pivot-bolt, 4, by which said lever is attached eccentrically upon the block C^2 . The pivot-bolt 4 is inserted through an eye formed through each of two lugs, c^9 , placed upon the rear side of the block C^2 , and at either side of its recess c^6 . A spur, e' , is formed upon one side of the lever at a point about midway of its length, for a purpose hereinafter described.

Figs. 9 to 12, inclusive, illustrate a modified form of my improved mechanism, operating on similar general principles, but somewhat differently arranged. The important distinction between the two forms here shown is that in the former the operating-lever acts directly upon the rack-bar, while in that now to be described the operating-lever acts indirectly upon the rack-bar through the medium of an interposed pinion. The modifications now to be described relate exclusively to the standard, the carrier-block, and the operating-lever, the remaining parts being identical with those previously described. In this form one of the sections of the standard B is formed with a long recess, b^3 , extending from near its top to near its bottom, for the purpose of accommodating the operating-lever connections when said lever is depressed. In this section the guide b^2 is omitted, the opposite section being alone provided with said guide, and the pin 3 passes through an eye formed in a projection above the upper terminus of the recess b^3 . The carrier-block in this instance is of substantially the same form as that previously described, but is provided with certain cams, 125 as hereinafter set forth. The dog D' in this instance is of substantially the same form as that previously described, and is attached in the same way; but the hooks d^2 are here dispensed with, the ledge c^4 , with a groove, c^{10} , formed beneath it, and stud c^5 , being here alone the means for retaining the block C^2 at the upper limit of its vertical movement, as hereinafter described.

At the lower corner of the block C² is attached the lower end of a curved arm, F, which extends outwardly and upwardly, and terminates at its upper end in an outwardly-bent portion, f. The inner side, f', of this arm inclines inwardly from its upper to its lower portion, and at the latter point a shoulder, f², is formed on the inner side of said arm, all for purposes presently to be stated. At the opposite lower corner of the block C² from that of the arm F is attached the lower end of a second arm, G, which extends outwardly and upwardly, its upper edge being concentric with and resting against the edge of the corresponding lug, e², and at its upper end said arm is bent outward at right angles, and then downward in the form of a broad outwardly-inclined cam, g. These cams F f' and G g' act, in connection with a sliding bar attached to the operating-lever E, in the manner and for the purposes hereinafter described. At its lower end the operating-lever E is formed with a box, H, provided at its inner end with two parallel lugs, h, each of which has an eye formed through its outer portion, and the under side of which is covered by a plate, h', securely joined to the main portion of said box, as shown. A groove, h², is formed longitudinally upon the under side of said box, and a transverse recess, h³, is also formed in each of its sides, near the inner ends thereof. A sliding bar, I, works in the groove h², and upon its under side is formed a groove, i, corresponding with the grooves h². Upon its front end the bar I is formed with a set of gear-teeth, i', similarly to the teeth e, previously described. Lying within the recesses h³ and the groove i is a bar, J, the ends of which are provided with oppositely-disposed oblique faces, j, which work against the sides of the recesses h³. The lever E, with its connection, is attached pivotally to the block C² by a pivot-bolt, 4, which passes through the eyes in the lugs e² of the block, and of the lug h of the box H. The lugs of the box H lie each outside of those of the block C². A gear-pinion, K, is centered upon the pivot-bolt 4, its teeth meshing constantly with those of the rack-bar C, and engaging or disengaging at will with the teeth i' of the bar I.

The operation of my improved mechanism is as follows: The carriage A is properly adjusted longitudinally upon the guide-rails A', so as to make room for the board to rest edge-wise upon the ends of the rails and against the faces of the standards. The carrier-blocks C², which may be supposed to have been left resting upon the lower blocks, C', are raised to the upper limits of their movements by raising the levers E and lifting said blocks C² up thereby. In case the mechanism first described be used, the elevation of the outer ends of the levers E depresses their inner ends and disengages the teeth e from the teeth c of the rack-bars C, so that the blocks may slide freely upward upon the rack-bars and between the guides b' b². During the latter portion of this

movement the ledges e⁴ and studs e⁵ carry the blocks past the pins 3 sufficiently to bring the hooks d² of the dogs D' above the pins 3, the spurs e' of the levers E at the same time entering between the rear faces of the standards B and the front faces of the stops C³. The blocks C² are now tilted back upon the upper ends of the guides b², so as to throw the hooks d² over the pins 3, after which the blocks C² are allowed to fall, and are caught by the hooks d' upon the pins 3, whereby their further descent is arrested, the levers E being also held from falling by the spurs e', resting against the stops C³. In case the modified form of mechanism be used, the lever is raised in the same way as before, by which movement the wedge-bars J are forced to one side by the contact of their contiguous ends with the cams g of the arms G, thereby retracting the sliding bars I and throwing the teeth i' out of engagement with the pinions K, so that said pinions are allowed to revolve freely upon the pivot-bolts 4 as the blocks C² ascend. At the upper limits of their movements the blocks C² are held from descent by the grooves c² beneath the ledges e⁴, which are brought into contact with the pins 3 by tilting each of the blocks C² backward upon the upper end of the guide b², as before. A board is now placed edgewise upon the ends of the rails A', with its side well up against the front faces of the standards A, after which the blocks C² are raised and tilted forward upon the upper ends of the guides b², so as to free said blocks from the pins 3, and are allowed to descend upon the rack-bars C until the dogs D' strike the upper edge of the board, the spurs e' in the meantime passing downward out of contact with the stops C³. As soon as the dogs D' strike the upper edge of the board, the levers E are depressed. In the arrangement first described this depression of the levers E first brings the teeth e into engagement with the teeth of the rack-bar C, then, as the levers E continue to descend, raises the rack-bar C and with it the blocks C', and causes the lower dogs, D, to come in contact with the under edge of the board, and both upper and lower dogs to bite well into the material. The final movement of descent of the levers E locks the rack-bars, so as to maintain the grip of the dogs. In the modified form of mechanism the descent of the levers E first causes the wedge-bars J to move in a direction opposite to that of their previous movement by engagement of their ends with the out-turned ends f and oblique sides f' of the arms F, thereby forcing the bars I inward and causing their teeth i' to engage with the teeth c of the rack-bars C. The further descent of the levers E rotates the pinion K upon the pivots 4, raising the rack-bars C and bringing the lower dogs, D, into contact with the lower edge of the board. The final movement of descent of the levers E causes the upper and lower dogs to bite well into the board, and locks the rack-bars C, so as to maintain the grip of the dogs. At the completion of the

descent of the levers E the boxes H rest at their under sides upon the shoulders f^2 of the arms F. The board is now ready for sawing, after which the levers are raised, as before, 5 and the blocks C² are caught upon the pins 3. After the board has been removed from the machine and a new one has been placed in position, the subsequent operations above described are successively repeated. In either 10 form of my device it will be seen that when the carrier-blocks C² are thus suspended upon the pins 3, the upper dogs, D', will be drawn backward within the standard to such an extent as to bring their outer extremities flush 15 with the forward faces of the standards, thereby avoiding any obstruction on the part of said dogs to the board while the latter is being placed upon the head-block. This retraction of the upper dogs is of the first importance in 20 devices of this sort, and the facility with which it is here accomplished renders my structure very useful and valuable in this respect also. Thus it will be seen that in either form above described my improved mechanism is simple 25 and durable in construction; also, that it is capable of very considerable adjustment, so as to receive materials of different widths, and, also, that all of its functions are performed in consequence of manipulations of a single member—30 the operating-lever E. The arrangement shown in Figs. 1 to 8 is that preferred by me on account of its greater simplicity over the form shown in Figs. 8 to 13. However, I here reserve to myself the right to make a separate 35 application for Letters Patent for the modified form of my invention herein described.

I do not confine myself to the precise construction herein described and shown, as various modifications of such construction may be 40 made without departing from the spirit of my invention; but,

Having now described my invention, what I claim as new is—

1. In a saw-mill dog, a vertical standard 45 formed in two parallel sections having guides upon their inner faces, and a rack-bar confined between said standard-sections in such manner as to have a limited vertical movement, and loosely confined at its lower end between said 50 guides, in combination with a dog upon the lower end of said bar to engage the under side of the board, a carrier-block mounted upon the rack-bar and movable vertically thereon, a dog upon the carrier-block to engage the upper 55 side of the board, and an operating-lever pivoted upon the carrier-block, and engaging at its inner end, directly or indirectly, with the rack-bar teeth, the said carrier-block being loosely confined between the said guides, and 60 the said operating-lever extending at right angles to the face of the standard through its rear

side, substantially as and for the purpose set forth.

2. In a saw-mill dog, a vertical standard composed of two parallel sections having guides upon their inner sides, and a rack-bar confined between said sections in such manner as to have a limited vertical movement therein, and loosely confined at its lower end between the said guides, in combination with a carrier-block confined loosely between the guides and movable vertically upon said rack-bar, a dog upon the lower end of said bar to engage the under side of the board, a dog upon the carrier-block to engage the upper side of the board, and an operating-lever pivoted upon said block, and provided at its inner end with a toothed segment to engage, directly or indirectly, with the rack-bar teeth, said lever extending at right 75 angles to the front of the standard through its rear side, substantially as and for the purpose set forth.

3. The vertical standard composed of two parallel sections having guides upon their inner faces, a rack-bar mounted within said standard in such manner as to have a limited vertical movement, and loosely confined at its lower end between said guides, a holding-bar secured transversely upon the upper end of said standard, and a catch projecting from the front face of said standard and mounted upon the said holding-bar, in combination with a dog upon the lower end of the rack-bar, a sliding carrier-block mounted upon the rack-bar, a dog mounted upon the block, and an operating-lever pivoted upon said block and engaging with the rack-bar teeth, the said block being arranged to engage with the holding-bar and to be held thereby at the upper limit of its vertical movement, and the lever being arranged to be held in elevated position by the catch at the upper limit of the vertical movement of the block, substantially as and for the purpose set forth.

4. The combination, with the vertical standard formed in two parallel sections having guides upon their inner sides, and the rack-bar loosely confined at its lower end between said guides, and provided with the vertically-elongated slot at its lower end, of the dog mounted upon the lower end of said bar, the carrier-block vertically movable upon said rack-bar, the dog and pivoted lever mounted upon said block, and the transverse pin passing through the standard-sections and through the rack-bar slot, substantially as and for the purpose set forth.

In testimony whereof I have hereunto set my hand this 8th day of June, A. D. 1883.

WALTER J. F. LIDDELL.
